GRAIN DUSTING MACHINE

Sampson J. Goodfellow, Regina, Saskatchewan,
Canada

Application March 22, 1937, Serial No. 132,399

8 Claims. (Cl. 83—28)

This invention relates to improvements in grain dusting machines and an object of the invention is to provide a device of the character herein described which is automatic in action and will thoroughly impregnate grain passed therethrough with any desired chemical dust.

A further object of the invention is to provide a device of the character herein described which is provided with a simple adjustment for varying the quantity of chemical dust discharged from the dust hopper.

A further object of the invention is to provide a device of the character herein described which is equipped with a mixing chamber in which is located a rapidly revolving wheel designed to produce through intermingling of the chemical dust and grain.

A further object of the invention is to provide a device of the character herein described which is designed with a rotating spinner in the discharge spout to preclude the possibility of free dust passing therethrough.

A further object of the invention is to provide a device of the character herein described in which the dust is discharged from the dust hopper in a great number of minute quantities.

A further object of the invention is to provide a device of the character herein described in which the dust hopper is provided with a novel type of agitator to prevent bridging of the dust therein.

A further object of the invention is to provide a device of the character herein described in which the rate of admittance of dust to the grain is dependent upon the rate of flow of grain into the mixing chamber.

A further object of the invention is to provide a device of the character herein described in which the chemical dust is drawn from the dust hopper by a collar affixed to a reciprocating rod extending into the hopper.

A still further object of the invention is to provide a device of the character herein described which is comparatively simple in construction, economical to manufacture and cannot easily become out of order.

With the above more important objects in view and such other minor objects as may appear as the specification proceeds, my invention consists essentially in the arrangement and construction of parts all as hereinafter more particularly described, reference being had to the accompanying drawings in which:

Fig. 1 illustrates a front elevational view of my improved type of grain dusting machine.

Fig. 2 is a side elevational view of the same.

Fig. 3 is a sectional view taken on the line 3—3 of Figure 1.

Fig. 4 is a perspective view of the agitator used in the dust hopper.

Fig. 5 is a perspective detail of the cam mechanism.

Fig. 6 is a perspective view of one of the rotor trays.

In the drawings like characters of reference 10 indicate corresponding parts in the different figures.

This invention has reference to an improved type of machine designed to dust seed grain to prevent the appearance of smut in the grain 15 after germination. The machine is adapted to use any of the various types of chemical dust now upon the market such as for example, copper carbonate, or the compounds sold under the trade names of Ceresan and Leytosan.

This invention consists of a framework 1 composed of four vertically disposed legs 2 which are joined by upper cross members 3 and intermediate cross members 4 and 5. Suitable braces 6 are also provided in order to produce a rigid 25 structure.

A grain hopper 7 is attached to the upper members 3 and converges downwardly into a short rectangular chute 8. Slidably mounted upon the side of the hopper is a gate 9 which extends through a slot 10 at the upper end of the chute. A lever 11 is pivotally attached to the hopper and projects outwardly beyond a guide 12 designed to limit the swinging movement of the lever. A short link 13 is secured by pins to both the lever and the gate and it will be apparent that with this arrangement, manual operation of the lever will cause the gate to close or open the lower end of the hopper.

The lower end of the chute 8 opens into an enlarged housing 14 which converges at the lower end into a spout 15 equipped with a mutually inclined surrounding lip 16 at the discharge end thereof. It should be mentioned that the point of entry of the chute into the housing is considerably offset from the central axis of the same for a reason presently to be explained.

Extending through the housing and supported within central bearings mounted upon the cross members 5 is a horizontally disposed rotatable 30 shaft 17. A rotor 18 is secured to the shaft within the housing and consists of six radial arms 19 each carrying a shallow tray 20 at the outer end thereof. Each of these trays during the course of rotation passes through a horizontal position 35

directly beneath the chute 8 and as well as functioning to revolve the rotor under the influence of grain falling thereonto, also serves to impart momentum to the rotor and finally acts as a fan 5 to create wind within the housing 14, thereby causing the maximum disturbance of air therewith.

Attached to the vertical side 21 of the grain hopper 7 is my dust hopper 22 which consists 10 of an elongated receptacle formed with a steeply inclined lower wall 23. A circular aperture 24 is provided adjacent the base of the hopper and is equipped with a flared lip 25 on the outer side thereof. This lip protrudes through a second 15 aperture into the chute 8.

Affixed to the cover of the rotor housing 14 and also to the wall of the chute 8 is a relatively heavy U-shaped member 27 having aligned orifices 28 in the vertically disposed legs 29 thereof. 20 Slidably mounted within these orifices is an elongated reciprocating rod 30 which extends across the chute 8 and through the aperture 24. A collar 31 is attached adjacent the end of the rod having a diameter slightly smaller than that of 25 the aperture 24. A dust agitator 43 is secured to the collar and consists of a length of wire turned to form a series of triangular elements 33, the apex of each element being downwardly disposed. This construction is highly important 30 as it has been found that by using an agitator of this configuration bridging of the dust in the hopper is entirely eliminated as the corners of the triangular dust section cut by the agitator continually crumble and eventually break down 35 the sectional mass.

Affixed to the rod 30 between the legs 29 of the supporting member 27 is an enlarged collar 34 which is maintained in position by a set screw 35. A compression spring 36 is interposed between 40 the collar and the outer leg of the support in order to urge the rod into the dust hopper as will be apparent. Threadably received within an orifice 37 is an adjusting screw 38 which may be locked in any desired position by the wing-nut 45 39. The head of this screw is designed to engage with the collar 34 to limit forward movement of the rod 30 and it will be evident that by adjusting this screw, the depth of penetration of the rod and consequently of the collar 31 into 50 the dust hopper may be varied.

Mounted upon the shaft 17 is a triple acting cam 40 consisting of a disc 41 from the face of which project three equi-spaced risers 42. One side of each riser is given arcuate formation 55 while the opposite side thereof is normally disposed with relation to the face of the disc. The direction of rotation of the disc is indicated by the arrow in Figure 5.

Attached to the central cross bar 4 is a bracket 60 43 upon which is pivotally mounted an inclined rocker arm 44. The lower end of this arm is formed into a finger 45 designed to engage with the risers 42 upon the face of the cam. The opposite end of this arm is twisted and bifurcated to pass on either side of the outer end of the rod 30. A small annular member 46 is secured to this rod and the end of the rocker arm is designed to engage therewith in order to shift the rod.

70 With this arrangement, it will be apparent that when the shaft 17 is rotated, the arm 44 will be given a rocking motion which will reciprocate the rod 30 through three full strokes during each revolution of the shaft. The rod is of course re- 75 turned in each stroke by the spring 36.

Extending between the inner walls of the spout 15 are three inclined baffle plates 47 which are designed to direct material falling thereon against an oppositely inclined baffle 48. Situated adjacent the lower edge of this baffle is a spinner 49 5 which spans the width of the spout and has a swastika sectional configuration. As material gravitates off the baffle 48, it strikes the spinner and rotates the same at a high rate of speed which ensures that all grain and dust will be 10 thoroughly mixed before discharge from the machine.

The structure of the device having been set forth, the mode of operation thereof will now be presented.

15 The hoppers 7 and 22 are first filled with grain and chemical dust respectively. The gate 9 is then opened permitting the grain to flow downwardly onto the trays 20 carried by the rotor. The weight of the grain will revolve the rotor 20 at a high rate of speed which will reciprocate the rod 30 through the medium of the arm 44 in the manner already described. This motion will cause the collar 31 to draw a predetermined amount of chemical dust through the aperture 25 24 at each stroke of the rod. This dust will also fall upon the trays 20 and due to the high speed of the rotor, a dust cloud will be formed in the housing 14 which will thoroughly impregnate the grain. As the mixture spills out of the trays, 30 it will gravitate into the spout 15 where it will pass between the plates 47 and strike the baffle 48. From here it will impinge against the spinner 49 rotating the same. This spinner serves to prevent any free dust from passing through the 35 machine as the rapid rotation of this member scatters the dust and ensures contact thereof with the grain.

In order that the machine may be used with any type of chemical dust, the adjusting device 40 38 has been provided which enables the length of the stroke of the rod 30 to be varied, thus changing the distance between the face of the collar 31 and the aperture 24. This change will 45 obviously alter the volume of chemical dust withdrawn from the hopper during each stroke. It should here be noted that the dust is admitted to the grain in a great number of minute quantities which precludes the possibility of any grain passing through the machine without coming in 50 contact with the dust.

During the operation of the machine, the rocker arm 44 is raised by the arcuate surfaces of the risers but drops rapidly off the edge thereof. This causes the spring 36 to snap the rod 55 30 back to its normal position which has a tendency to shake the machine and ensure thorough agitation of the dust within the hopper.

It should finally be mentioned that the speed of revolution of the rotor is of course dependent 60 upon the quantity of grain gravitating thereon and as the quantity of dust discharged from the hopper is dependent upon the speed of rotation of the rotor, it follows that dust will be discharged into the mixing chamber in proportion 65 to the amount of grain admitted thereto.

From the foregoing, it will now be apparent that I have provided a highly efficient type of grain dusting machine which is characterized by simplicity and high efficiency.

70 Since various modifications can be made in the above invention, and many apparently widely different embodiments of same, made within the scope of the claims without departing from the spirit and scope thereof, it is intended that all 75

matter contained in the accompanying specification shall be interpreted as illustrative only and not in a limiting sense and I desire only such limitations placed thereon as are specifically expressed in the accompanying claims.

5 What I claim as my invention is:

1. A machine for coating with dust the constituents of a granular mass of material comprising, in combination, a framework, a hopper provided with a material discharge aperture secured to said framework, a rotor, a housing for said rotor, a dust container having a dust discharge aperture communicating with said housing and a material discharge chute at the base of said framework, said rotor consisting of a shaft journalled for rotation upon said framework, a plurality of radiating arms secured to said shaft and a material receiving pan secured to the outer end of each arm and acting to produce air disturbance within said housing, the said discharge aperture of said hopper being located above said rotor, to one side of said shaft and substantially in vertical alignment with said pans when the latter are in horizontal position, dust dispensing mechanism 10 in association with said dust container, and means operatively connecting said rotor and said dust dispensing mechanism to drive the dispensing mechanism from the rotor.

2. The machine as defined in claim 1 in which 15 said dust container comprised with a surrounding wall and a base, said dust discharge aperture being positioned at the base of said wall, said dust dispensing mechanism comprises an end-shiftable member extending through said aperture into said container.

3. The machine as defined in claim 1, which 20 includes a secondary rotating element journalled in said discharge chute to effect a final commingling of said dust with said material prior to discharge of the matter from said machine.

4. A machine for coating with dust the constituents of a granular mass of material comprising, in combination, a framework, a hopper provided with a material discharge aperture secured to said framework, a rotor, a housing for said rotor, a material dust container having a dust discharge aperture communicating with said housing and a discharge chute at the base of said framework, said rotor consisting of a shaft and a plurality of radiating arms secured thereto, a material receiving pan being secured to the outer end of each arm and acting to produce air disturbance within said material housing, the said discharge aperture of said hopper being located above said rotor to one side of said shaft and substantially in vertical alignment with said pans when the latter are in horizontal position, dust dispensing mechanism in association with said dust con-

tainer and means for actuating said dust dispensing mechanism consisting of a pivoted rocker arm extending between said shaft and said dust dispensing mechanism, the said rocker arm being in bearing engagement with said dust dispensing mechanism, and a cam upon said shaft, said rocker arm being also in bearing engagement at one end thereof with said cam and mounted for movement in a plane normal to the plane of rotation of said rotor.

5. The device as defined in claim 4 in which 10 said dust dispensing mechanism includes an elongated and spiraled end-shiftable triangulated wire agitator extending into said dust container.

6. A machine for coating with dust the constituents of a granular mass of material comprising, in combination, a framework, a hopper provided with a material discharge aperture secured to said framework, a rotor, a housing for said rotor, a material dust container having a dust 15 discharge aperture communicating with said housing and a discharge chute, said rotor consisting of a shaft and a plurality of radiating arms secured to said shaft, a material receiving pan being secured to the outer end of each arm and acting to produce air disturbance within said material housing, the said discharge aperture of said hopper being located above said rotor to one side of said shaft and substantially in vertical 20 alignment with said pans when the latter are in horizontal position, dust dispensing mechanism in association with said dust container, means operatively connecting said rotor and said dust dispensing mechanism to drive the dispensing mechanism from the rotor, said dust container 25 comprising a surrounding wall and a base, an aperture being provided at the base of said wall, said dust dispensing mechanism consisting of an end-shiftable member extending through said dust discharge aperture into said container.

7. The device as defined in claim 6 which 30 includes a pivoted rocker arm upon said framework, said rocker arm extending between said end-shiftable member and said shaft, a cam secured to said shaft, one end of said rocker arm being in engagement with said cam to actuate said end-shiftable member upon rotation of said rotor in a direction normal to the plane of rotation of said rotor, the opposite end of said rocker arm being in bearing engagement with said end-shiftable 35 member.

8. The machine as defined in claim 6 in which 40 a secondary rotating element is journalled within said material discharge chute to effect a final commingling of said dust with said material prior to discharge of the latter from said machine.

SAMPSON J. GOODFELLOW.
